US00D910913S

(12) **United States Design Patent** (10) **Patent No.:** **US D910,913 S**
(45) **Date of Patent:** **** Feb. 16, 2021**

(54) **POD FOR AN ELECTRONIC VAPORIZER**

- (71) Applicant: **Altria Client Services LLC**,
Richmond, VA (US)
- (72) Inventor: **Charles P. Kauss**, Atlanta, GA (US)
- (73) Assignee: **Altria Client Services LLC**,
Richmond, VA (US)
- (**) Term: **15 Years**
- (21) Appl. No.: **29/681,321**
- (22) Filed: **Feb. 25, 2019**

Related U.S. Application Data

(57) **CLAIM**

The ornamental design for a pod for an electronic vaporizer, as shown and described.

DESCRIPTION

FIG. 1 is a perspective front view of a pod for an electronic vaporizer.

FIG. 2 is a front view of the pod for electronic vaporizer of FIG. 1.

FIG. 3 is a rear view of the pod for electronic vaporizer of FIG. 1.

FIG. 4 is a right side view of the pod for electronic vaporizer of FIG. 1.

FIG. 5 is a left side view of the pod for electronic vaporizer of FIG. 1.

FIG. 6 is a top view of the pod for electronic vaporizer of FIG. 1; and,

FIG. 7 is a bottom view of the pod for electronic vaporizer of FIG. 1.

In the drawings, the dash-dot-dash broken lines represent boundaries and forms no part of the claim; the evenly spaced broken lines depict portions of the pod for an electronic vaporizer and form no part of the claimed design.

1 Claim, 5 Drawing Sheets
